DESIGN FOR A VELOCIPED

Willard M. Bashaw and Willis Olin Dixon,
Wichita, Kans.

Application May 3, 1946, Serial No. 129,298

Term of patent 3½ years

(Cl. D34—15)

To all whom it may concern:

Be it known that we, Willard M. Bashaw and Willis Olin Dixon, citizens of the United States, residing at Wichita, in the county of Sedgwick and State of Kansas, have invented a new, original, and ornamental Design for a Velocipede, of which the following is a specification, reference being had to the accompanying drawing, forming a part thereof.

Fig. 1 is a perspective view of a velocipede embodying our new design; and

Fig. 2 is a rear elevational view of the velocipede shown in Fig. 1.

We claim:

The ornamental design for a velocipede, substantially as shown.

WILLARD M. BASHAW.
WILLIS OLIN DIXON.
